UNITED STATES PATENT OFFICE

160,751

COMBINED PURSE AND COMPACT

Herman M. Talcove, Roxbury, Boston, Mass.

Application November 17, 1949, Serial No. 6,091

Term of patent 3½ years

(Cl. D87—3)

To all whom it may concern:

Be it known that I, Herman M. Talcove, a citizen of the United States of America, residing at Roxbury, in the city of Boston, county of Suffolk, and Commonwealth of Massachusetts, have invented a new, original, and ornamental Design for Combined Purse and Compact, of which the following is a specification, reference being had to the accompanying drawing, forming part thereof.

Fig. 1 is a top plan view of a combined purse and compact, showing my new design;

Fig. 2 is a front elevational view thereof with the cover of the compact element raised;

Fig. 3 is an end elevation of the combined purse and compact; and

Fig. 4 is a top plan view thereof with the purse element in an open position.

I claim:

The ornamental design for a combined purse and compact, substantially as shown.

HERMAN M. TALCOVE.
